FIG. 18

FIGS. 1-6 are respectively top, left, front, right, rear and bottom views of a bookmark showing my new design wherein the depending tab portion is triangularly shaped;

FIGS. 7-12 are respectively top, left, front, right, rear and bottom views of another embodiment thereof wherein the depending tab is pentagonally shaped; and

FIGS. 13-18 are respectively top, left, front, right, rear and bottom views of a further embodiment thereof wherein the depending tab is shield shaped.

I claim:

The ornamental design for a bookmark, substantially as shown and described.
